WIRE PULLING JACK

Edward J. Dullaghan, Boise, Idaho

Application April 19, 1951, Serial No. 221,841

4 Claims. (Cl. 140—123.5)

1

This invention relates to a tool for tightening and tying concrete form tie wires, and is more particularly designed as an improvement over the tool shown in applicant's prior Patent No. 2,492,560.

The principal object of the invention is to provide a simple, light-weight, portable tool which will first exert a relatively great pull upon concrete form wires, and then act to twist the two extremities of the wire together to form a permanent tie.

Another object of the invention is to relieve the strain ordinarily imposed upon the operator by providing a built-in hydraulic jack for exerting the pulling action on the wire and by providing means in the jack for maintaining the fluid therein in effective position at all positions of the tool.

Further objects are to provide an effective gripping means for gripping the extremities of the wire, and to provide an easily operated twisting device which will form a tight locking twist in the wire without burning, breaking, or damaging the wire.

Other objects and advantages reside in the detail construction of the invention, which is designed for simplicity, economy, and efficiency. These will become more apparent from the following description.

In the following detailed description of the invention, reference is has to the accompanying drawing which forms a part hereof. Like numerals refer to like parts in all views of the drawing and throughout the description.

In the drawings:

Fig. 1 is a top view of the improved concrete form wire pulling and tying tool as it would appear with a wire in place therein ready for use;

Fig. 2 is a side view thereof;

Fig. 3 is a longitudinal, horizontal section, taken on the line 3—3, Fig. 2;

Fig. 4 is a fragmentary, front view thereof;

Fig. 5 is a fragmentary, detail section, taken on the line 5—5, Fig. 3;

Fig. 6 is a similar section, taken on the line 6—6, Fig. 3; and

Fig. 7 is a cross-section through a wire tying head used on the improved tying tool, taken on the line 7—7, Fig. 3.

In the drawing a typical concrete form has been indicated at 10, with one of its supporting batten strips at 11 and form-typing wires at 12.

The invention is designed to apply tension to the wires 12 and to twist the extremities

2

thereof together to form a tying twist 13. The improved tool is built about a supporting frame member 14 provided with a downwardly depending handle socket 15 into which any suitable handle 16 may be inserted, if desired.

A cup-like fluid reservoir 17 is threaded onto a receiving boss 18 on the frame member 14. The reservoir contains a valve block 19 secured against the closed extremity thereof by means of a tubular, threaded stud 20 and a clamping nut 21.

An actuating cylinder 22 extends through the frame member 14 and is threaded into the valve block 19 within the reservoir 17. A power piston 23 is slideable within the cylinder 22. Fluid 15 is pumped from the reservoir into the actuating cylinder by means of a pump plunger 23 operating in a pump cylinder 24. The pump cylinder 24 extends from the frame member 14 to the valve block 19 parallel to the actuating cylinder 22, and the plunger 23 extends to the exterior through a suitable packing nut 25. As the plunger 23 is moved outwardly, it acts to draw fluid from the reservoir through an intake port 26 and through a return check valve ball 27, and as the plunger 23 is moved inwardly, the check valve ball 27 opens, and a second check valve ball 29 opens, allowing the fluid to enter the cylinder 22 through an intake port 30. The ball 27 is urged against its seat by means of a spring 28, and the second check valve ball 29 is constantly urged toward a seat bushing 31 by means of a second spring 32.

The plunger 23 is reciprocated by means of an L-shaped pump lever 33 rotatably mounted in supporting ears 34 extending forwardly from the frame member 14. The pump lever 33 terminates in a crank member 35 which is connected with the plunger 23 through the medium of a suitable crank pin 36. The pump lever 33 may be provided with a convenient hand grip 37. Thus, it can be seen that as the grip 37 is moved forward and back, the pump plunger will be moved forward and back at reduced speed and increased leverage.

45 A safety valve ball 38 is held in place against a retaining spring in the threaded stud 20 by means of a threaded plug 39. The ball 38 is set to release at any desired, predetermined pressure. The fluid released by the safety valve returns through a return channel 40 to the reservoir 17.

The fluid pressure in the actuating cylinder 22 can be released by means of an L-shaped releasing lever 41 which is also rotatably mounted 55 in the ears 34. The lever 41 carries a releasing

cam 39 positioned to contact a valve push rod 40 which acts to force a stop valve ball 41 from its seat against the action of a third valve spring 42.

A compression spring 43 acts against a set collar 44 on the rod 40 to constantly urge the latter against the cam 39. Leakage around the rod 40 is prevented by means of a suitable gland nut 45. It can be seen that if the releasing cam 39 is turned to the position of Fig. 5, the pressure in the actuating cylinder 22 will be released and the fluid therein will flow back to the fluid reservoir 17.

Since it is necessary to use the device in all positions, it is essential that some means be provided for maintaining the fluid about the pump cylinder 24. This is accomplished by placing an inflatable air bag 46 in the reservoir which can be inflated with air through an air valve 47, which may be similar to the usual valves used on pneumatic tires. As fluid is drawn from the reservoir 17, the pressure within the bag 46 will cause the bag to expand and prevent the formation of a void in the reservoir. When fluid is returned to the reservoir, the air in the inflated bag will compress, allowing the bag to contract. Therefore, regardless of the position of the tool, the intake port 26 of the pump cylinder 24 will always be immersed in fluid.

The power piston 48 is mounted on the extremity of a square piston rod 49 which extends from the cylinder through a square opening in a cylinder head 50. The cylinder head 50 is mounted on the forward extremity of a rotatable wire-gripping member 51 by means of suitable mounting screws 52. The wire-gripping member 51 is counter-bored to rotatably receive a retaining ring 53 which is threaded on the extremity of the actuating cylinder 22. A fluid sealing disc 54 is clamped between the head 50 and the end of the cylinder. The gripping member 51 is thereby held in place by the retaining ring 53, but is freely rotatable about the actuating cylinder 22.

The gripping member 51 carries a transversally-extending, lower dog shaft 55 on each extremity of which a lower ratchet dog 56 is mounted. A side plate 57 is secured on each extremity of the shaft 55 by means of retaining screws 58 threaded into the extremities of the shaft. The shaft 55 is positioned below the axis of the piston rod 49. A transverse, eccentric shaft 59 is journaled in the wire-gripping member 51 above the axis of the rod 49 and is provided with a grip clamping wheel 60. An eccentric crank stub 61 projects from the eccentric shaft 59 upon which two upper ratchet dogs 62 are mounted. The adjacent faces of the two pairs of dogs are provided with ratchet-like gripping teeth 63 for gripping the extremities of the wire 12.

A third retaining screw 64 is threaded into the extremity of the eccentric stub 61 to assist in holding the side plates 57 and the dogs in place. The side plates 57 are movable with the eccentric action of the stub 61, and are provided with elongated screw holes 65 to allow for movement relative to the lower dog shaft 55. The amount of tilting action of the dogs is limited by means of limiting pins 66 extending into elongated, arcuate pin holes 67.

A wire-twisting head 71 is fixedly mounted on the extremity of the piston rod 49 and held in place thereon by means of a suitable retaining pin 68. A pivot point 70 is inset in the end of the rod 49 and projects axially forward therefrom. The wire-twisting head 71 is provided

with two diametrically opposite, wire-receiving passages 86, the outer walls of which are substantially parallel to the axis of the head. The inner walls of the passages 86, indicated at 68, 5 are arcuately inclined inwardly, as shown in Fig. 3, and terminate in a round, countersunk, twist-receiving cavity 90. The rear extremity of the twisting head is surrounded by a circular ratchet flange 73 provided with peripheral 10 ratchet notches 74.

An annular ratchet yoke 75 surrounds the flange 73. The ratchet yoke 75 is held in place about the notched ratchet flange 73 of the head by means of a circular back plate 72 and an 15 annular front plate 76, which are secured to the yoke 75 by means of suitable screws 77. The yoke 75 is provided with a ratchet handle 78 having a pawl cavity 79 in which a ratchet pawl 80 is mounted on a pawl pivot pin 81. The 20 pawl 80 is urged into the ratchet notches 74 by means of a radial plunger 82 mounted against a compression spring 84 in a rotatable latch shaft 83. The latch shaft extends through the front plate 76, where it is provided with a finger 25 grip 85.

It can be seen that when the latch shaft 83 is swung in one direction, by means of the grip 85, the plunger 82 will move away from the pawl 80, allowing it to swing away from engagement 30 with the notches 74, and when moved in the other direction, as shown in Fig. 7, the plunger will swing against the pawl and the spring 84 will force the pawl into engagement with the notches.

35

Operation

The extremities of the tie wire 12 are drawn through the form 10 on each side of the batten 11. The pivot point 70 is placed against the batten between the extremities of the wire, and the latter are passed through the wire-receiving passages 86 in the twisting head 71, thence between the two dogs 56 and 62 at each side of the gripping member 51, as shown in the drawing.

The grip clamping wheel 60 is now rotated 45 rearwardly to swing the upper dogs 62 downwardly toward the dogs 56 and into gripping relation with the extremities of the wire. The pump lever 33 is now operated to force the actuating cylinder 22 rearwardly along the piston rod 49 so as to force the pivot point into the batten and to increase the tension in the wire 12. When the predetermined tension has been reached, the safety valve ball 87 will release to prevent further rearward movement.

The ratchet handle 78 is now oscillated to intermittently rotate the twisting head 71. The rotation of the winding head is transmitted through the square piston rod 49 to the gripping member 51 so that all elements of the tool which are connected to the wire will rotate around the axis of the pilot point 70 to form the twist 13 in the cavity 90. The advancing twist in the wire increases the pull upon the actuating cylinder and consequently tends to increase the fluid pressure in the cylinder 22. The pressure increase is gradually released by the safety valve ball 87 so that with the proper safety valve setting the exact tension necessary to produce a tight, perfect twist in the wire is maintained throughout the twisting action, and all damage to the wire is eliminated.

After the twist is completed, the hand wheel 60 is rotated to release the ratchet dogs from the wire and the tool is withdrawn therefrom.

While a specific form of the improvement has been described and illustrated herein, it is to be

understood that the same may be varied, within the scope of the appended claims, without departing from the spirit of the invention.

Having thus described the invention, what is claimed and desired secured by Letters Patent is:

1. A tool for tightening and tying concrete form tie wires comprising: a frame member; a cup-like reservoir mounted on said frame member and extending rearwardly therefrom; an actuating cylinder mounted in and extending through said frame member and projecting into said reservoir and forwardly from said frame member; a non-round piston rod slidably mounted in said cylinder; means for pumping fluid from said reservoir into said cylinder to force said piston rod forwardly therein; a cylinder head in said cylinder having a non-round opening through which said rod slidably passes; a sleeve rotatably mounted about the forward extremity of said cylinder; means for preventing longitudinal movement of said sleeve with respect to said cylinder; wire-gripping members mounted on opposite sides of said sleeve, said sleeve being attached to said cylinder head to rotate therewith and with said rod; and a wire-twisting head fixedly mounted on the extremity of said piston rod and having wire passages in alignment with said wire-gripping means.

2. A tool for tightening and tying concrete form tie wires as described in claim 1 and having yieldable means allowing said sleeve to approach said twisting head as the tension in the wire increases due to the twisting action thereon.

3. A tool for tightening and tying concrete form tie wires as described in claim 2 having means swingingly mounted on said twisting head for imparting intermittent rotation thereto.

4. A tool for tensioning and twisting a concrete form tie wire, comprising: a piston rod; a wire-twisting head fixedly mounted on the forward extremity of said piston rod and provided with two oppositely positioned wire-receiving passages; a pivot point projecting forwardly from said rod; an actuating cylinder surrounding said rod in relatively rotatable relationship; a piston on said rod within said cylinder; means for forcing fluid under pressure into said cylinder against said piston to force said cylinder rearwardly on said rod; means rotatably mounted on said actuating cylinder for attaching the extremities of a form-tying wire thereto, said means being non-rotatable relative to said rod so that the winding of said wire will act to draw said cylinder forwardly on said rod to increase the fluid pressure in said cylinder; and a safety valve arranged to relieve the pressure in said actuating cylinder when a predetermined pressure has been reached therein to avoid excessive tension in said wire.

EDWARD J. DULLAGHAN.
